UNITED STATES PATENT OFFICE.

HERBERT N. RIDGWAY, OF WINTHROP, MASSACHUSETTS, ASSIGNOR TO AUTOMOTOUS BOAT COMPANY, OF BOSTON, MASSACHUSETTS, A CORPORATION OF MASSACHUSETTS.

SUBMARINE-BOAT STRUCTURE.

SPECIFICATION forming part of Letters Patent No. 731,500, dated June 23, 1903.

Application filed January 22, 1903. Serial No. 140,148. (No model.)

To all whom it may concern:

Be it known that I, HERBERT N. RIDGWAY, a citizen of the United States, residing at Winthrop, in the county of Suffolk and State of Massachusetts, have invented an Improvement in Submarine Structures, of which the following description, in connection with the accompanying drawing, is a specification, like letters on the drawing representing like parts.

The invention herein to be described and exemplified in a boat or vessel has for its object more especially to provide a structure of the kind referred to the top of which is normally below the water-level with a conning tower that may be projected from the water over the top of the boat or vessel. The conning-tower has water-tight fit in the top of the vessel, and the open upper end of the tower is provided with a cover mounted on a carrier adapted to be moved by actuating devices to lift the cover from the upper end of the tower when above the water and also to close said cover water-tight before the tower is retracted into the vessel. The tower, that it may be moved vertically, is connected with a piston fitting a cylinder and adapted to be moved therein longitudinally of the axis of the tower by a fluid to thereby project the tower and its closed cover above the water. The piston connected with the conning-tower is bored for part of its length from its upper end and receives the cover-carrier, shown also as a piston. The tower-moving piston has a connected central sleeve provided with a disk on which are erected certain tower-sustaining rods, and the central sleeve fits and is slidable over the cylinder in which the tower-moving piston works. The piston for moving the tower vertically has connected with it and the upper interior of the tower the upper end of a spiral stairway, the lower end of said stairway being sustained by the sleeve connected with said piston near its lower end.

The drawing shows my invention in submerged vessel or boat in one approved form.

In the drawing, A represents a vessel or boat the body of which is shown as of fish shape; but which may be of any desired shape.

The top or deck A' of the vessel or boat is shown as submerged below the water-level B, and the stern of the vessel has a propeller B', which may be rotated in any usual manner not necessary to be herein shown. The interior of the vessel may be divided up into compartments in any usual manner, not necessary to be herein shown, and the body of the vessel may be composed of any usual materials united into the desired outline or shape in any usual manner.

The chief feature of invention to be herein specifically described and claimed relates to the conning-tower, and I will now describe the same. This tower comprises a circular curb or wall C shown as sustained by rods C', connected with a disk C², to be described. The exterior of the curb has a water-tight fit in a packed gasket D, secured water-tight to the body in usual manner and having a ring-shaped follower D' to meet the packing D² and force the same water-tight against the curb C.

Instead of the gasket shown I may use any other equivalent means for securing a water-tight fit for the curb. The disk C² has rising from it a sleeve C³, the upper end of which at a point above the cylinder a, which may be erected on a fixed head or plate a' by screws a², is fixed to the exterior of the tower-moving piston C⁴.

Between the exterior of the upper portion of the piston C⁴ and the interior of the tower I have arranged a spiral staircase E, that is fixed with relation to said piston and tower, and said stairs at the lower end thereof embrace the sleeve C³ and meet substantially the disk C², so that the tower, its piston, and the stairs move together as the tower is projected from the top of the vessel above the water-line.

The piston C⁴, the lower end of which enters the cylinder a, is bored for part of its length to leave a chamber a⁴, in which enters the cover-carrier a⁵, shown as a piston-rod depending from the cover G, shown as a circular plate, there being a packing b of any usual construction that when the cover is made to contact with the upper end of the

curb of the tower will close said upper end water-tight. The head a' of the cylinder has connected with it a pipe b' for the admission of a fluid into the cylinder a to raise the piston and tower and project the top of the closed cover above the water-level. The pipe b' has a three-way valve b^2 , that may be turned into a position to enable the water forced into the said cylinder to pass away outside the vessel or into any usual well as the piston descends to retract the tower below the water-level. The upper end of the sleeve and the chambered part of the piston receives a pipe c , preferably a flexible or hose pipe, to conduct a fluid into the chamber a^4 . The pipe c has a valve c' with suitable ways to permit water to enter chamber a^4 and to leave said chamber. The pipe c below the valve c' is passed through the disk C^2 and coiled inside the circular well G^3 , in which the disk C^2 is located, said pipe being led through said well. This coiling of the pipe permits the piston C^4 and head C^2 to rise and fall and with it the pipe c and valve c' .

25 When water is admitted through pipe b' into the cylinder in which the lower end of the piston C^4 stands, the piston and tower, stairs, and cover, then covered by the water, are raised until the top of the tower rises 30 above the water-line into the dotted-line position, and thereafter the valve c' is opened to admit water into the chamber a^4 , which acting immediately on the lower end of the carrier a^5 lifts the cover G into the dotted-line 35 position. With the top of the tower at the proper position above the water-level and the cover open a person may walk up the stairs and may look in all directions or might take a small boat or step on a dock properly located for the purpose, and in this way, if desired, a person may leave the vessel and return the same way. A person having viewed the horizon for a proper period may pass down the stairs and after turning the valve c' to 40 let the water escape from the chamber a^4 the carrier and cover will descend on the open upper end of the tower and close the same water-tight, and then an attendant by a suitable wrench inserted through a hole d in the 45 disk C^2 will turn the valve b^2 and let the water escape from the cylinder a , during which time the tower is retracted into the vessel below the water-line or substantially as shown by full lines in the drawing.

50 The curb and piston may be of any suitable length, according to the conditions of use of the vessel, the water, &c.

The curb will have preferably suitable windows e , through which a person may see 55 when the upper end of the tower is above the water-line.

Having described my invention, what I claim, and desire to secure by Letters Patent, is—

65 1. A vessel, a conning-tower having a water-tight fit in the top of said vessel, a cover

adapted to shut water-tight on said tower, means to move the end of said tower outwardly from the top of said vessel, and means to thereafter remove said cover from said tower.

2. A vessel, a conning-tower having a water-tight fit in the top of said vessel, a stairway inside said tower, a cover to shut said tower water-tight where exposed at the top of said vessel, means to elevate said tower and stairs in said vessel to project the tower above the water-line, and means to thereafter automatically remove the cover from said tower.

3. A vessel, a conning-tower having its upper end fitted water-tight in the top of said vessel, a piston connected with said tower, a cylinder to contain said piston, a cover to close said tower water-tight, means to permit the entrance of fluid into said cylinder to actuate said piston and project the tower from the top of the vessel, a carrier connected centrally with said cover and entering the tower-moving piston, and means to permit fluid to enter said tower-moving piston to move the cover and open the end of the tower above the water-line.

4. In a vessel, a well, a cylinder erected in said well, a conning-tower, a piston carrying the same and entering said cylinder, a sleeve connected with said piston and having a disk entering said well, said disk having a hole, and a pipe located in said well and having a valve that may be reached through the hole in said disk.

5. In a vessel, a well, a cylinder erected in said well, a conning-tower having a water-tight fit in the top of said vessel and having a connected piston entering said cylinder, a sleeve connected with said piston and surrounding said cylinder, said sleeve having a disk entering said well, a cover for said tower, and means to admit a fluid to said cylinder to project said closed tower for the desired distance above the top of said vessel.

6. In a vessel, a well, a cylinder erected in said well, a conning-tower having a water-tight fit in the top of said vessel and having a connected piston entering said cylinder, a sleeve connected with said piston and surrounding said cylinder, said sleeve having a disk entering said well, a cover for said tower, means to admit a fluid to said cylinder to project said closed tower for the desired distance above the top of said vessel, and means to admit fluid into the upper part of said piston to raise said cover from said tower after the latter has been projected above the water-line.

In testimony whereof I have signed my name to this specification in the presence of two subscribing witnesses.

HERBERT N. RIDGWAY.
